Patented Apr. 19, 1921.

UNITED STATES PATENT OFFICE.

ED MURRAY, OF LINCOLN, NEBRASKA.

METHOD OF CONTROLLING SUBTERRANEAN STREAMS.

1,374,945.

Specification of Letters Patent. Patented Apr. 19, 1921.

Application filed April 25, 1919. Serial No. 292,531.

To all whom it may concern:

Be it known that I, ED MURRAY, a citizen of the United States, residing at Lincoln, in the county of Lancaster and State of Nebraska, have invented certain new and useful Improvements in Methods of Controlling Subterranean Streams; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a method of and means for controlling the flow of subterranean streams whereby the water may be preliminarily stored or caused to accumulate for the purpose of utilizing it as a power medium as, for example, by directing it from a conduit to a source of consumption such as a water turbine or the like.

It is well known that subterranean streams generally flow incessantly and it is generally estimated that there is a drop of at least seven feet to the mile. It is, therefore, obvious that if the power of such stream could be utilized for industrial or commercial purposes, a very valuable adjunct to the industrial development of a community would be provided.

In carrying out my invention I prefer to erect a barrier across the stream to impound the water and direct it through a conduit or flume from which it may be discharged to a hydraulic motor as, for example, a water turbine. In practice I prefer to have a drop in the flume less than the natural drop of the flowing stream so that water may accumulate at least as fast as it is consumed, the off-take generally being less than the amount of water accumulated. I have found that a reservoir may be provided by erecting two converging walls in the path of the stream and extending these walls downwardly to a point at least beneath the water gravel as, for example, upon bed rock or shale, removing the dirt from between the walls and erecting a conduit or flume at the point of convergence of the walls so that the accumulated water will be directed thereto to be discharged against a suitable hydraulic motor. The walls may extend a suitable distance above the ground so that there will be a sur-

face accumulation of water and for convenience I may erect the flume upon the ground below the extended water level so that there will be hydraulic pressure exerted through the flume against the hydraulic motor, the pressure depending upon the size of the reservoir and the back pressure of the water confined therein.

In the drawings,

Figure I is a vertical longitudinal sectional view through a reservoir and the flume constructed in accordance with my invention, and

Fig. II is a plan view of the same.

Referring now to the drawings by numbers of reference:

1 and 2 designate two vertical converging walls submerged a suitable distance below the ground as, for example, below the water gravel or bed of the subterranean stream. By "water gravel" I mean the strata through which the subterranean stream flows. The dirt is then removed from between the walls and a flooring 7 is preferably provided, which may consist of a layer of concrete or similar material so that a basin 8 is formed. The basin is preferably covered or roofed over by a suitable roofing 9, which may consist of concrete or similar material built over a form in the usual way.

At the point of convergence of the walls is arranged a flume 3, which may consist of a concrete conduit having an inlet 4 and an outlet 5. There is spaced across the walls in front of the flume a perforate wall or guard 6 to prevent any solid matter passing through the flume 3. The inlet to the flume 3 is provided with a sliding gate valve 10 of usual construction, which may be operated in any well known manner.

The flume generally rests upon the ground and will have a drop less than the natural drop of the subterranean stream so that the water will flow through the flume at a velocity less than the velocity of the stream and thereby permit an initial accumulation which may assist in increasing the velocity through the flume due to hydrostatic pressure due to such accumulation. The diverging walls and the water gate constitute a barrier in the path of the flow of the stream so that the water accumulated in the basin can pass out only through the flume 3.

It will, therefore, be apparent that the power may be derived from the natural flow

of the subterranean stream in a most efficient manner.

Having thus described my invention, what I claim as new therein, and desire to secure 5 by Letters-Patent, is:

1. The method of controlling subterranean streams which consists in erecting a barrier across the path of flow of the stream below the surface of the earth and extending 10 the barrier above the earth's surface, and

tapping the barrier near the top thereof to provide a water supply.

2. In combination with a subterranean stream, of converging walls extending from the bed of the stream to a point above the 15 earth's surface, and a flume connected to the walls at the point of convergence, said flume being above the subterranean stream.

In testimony whereof I affix my signature.

ED MURRAY.
